HABERDASHERY HANGER

Joseph A. Larkin, 27 Crestwood Drive,
Council Bluffs, Iowa

Filed July 23, 1965, Ser. No. 86,268

Term of patent 14 years

(Cl. D80—8)

Fig. 3

Fig. 1

Fig. 4

Fig. 5

The dominant features of my design reside in the portions shown in full lines.

I claim:

The ornamental design for a haberdashery hanger, as shown and described.
